UNITED STATES PATENT OFFICE.

CHARLES F. KARBERG, OF CLEVELAND, OHIO, ASSIGNOR TO THE CLEVELAND-AKRON BAG COMPANY, OF CLEVELAND, OHIO, A CORPORATION OF OHIO.

DESIGN FOR A GEAR-CASE.

47,429.

Specification for Design.

Patented June 8, 1915.

Application filed February 8, 1915. Serial No. 6,860. Term of patent 14 years.

To all whom it may concern:

Be it known that I, CHARLES F. KARBERG, a citizen of the United States, residing at Cleveland, county of Cuyahoga, and State of Ohio, have invented a new, original, and ornamental Design for a Gear-Case, of which—

Figure 1 of the drawing is a plan view, Fig. 2 a front elevation, and Fig. 3 a side view, of a gear case, showing my new design.

I claim:

The ornamental design for a gear case, as shown.

CHARLES F. KARBERG.

Witnesses:

FRANK C. LOHISER,
F. J. GREER.
